BUCKET

Thomas F. Banigan, Kenmore, N. Y., assignor to
 Du Pont Rayon Company, New York, N. Y., a
 corporation of Delaware

Application March 29, 1933, Serial No. 663,264

2 Claims. (Cl. 118—1)

This invention relates to the use of centrifugal apparatus for the manufacture of artificial thread, horsehair, straw, or the like, such as threads of regenerated cellulose or of cellulose derivatives. The invention will be described in connection with the process of producing regenerated cellulose threads from viscose, but the particular description does not limit the invention.

10 In one method of manufacturing artificial thread by the viscose process, the freshly spun thread is collected in a rapidly revolving bucket which, to provide for safety and for the removal of liquids and gases, is located in a bucket compartment provided with drainage and ventilation. The rapidly revolving bucket throws out a spray of coagulating bath which saturates the air within the compartment. If the rate of removal of the saturated gas from the compartment by the 20 ventilating system is slow, crystals form in the compartment and on the outside of the bucket, increasing considerably the power necessary to rotate the bucket, particularly during the latter stages of the spinning cycle. Heat is mechanically developed within the bucket compartment, and the ventilating system fails to cool the interior of the compartment sufficiently.

25 The adoption of high bucket speeds, has accentuated the difficulty of bucket compartment ventilation and has tended to increase crystal formation. Ventilation is frequently so bad that with high bucket speeds sufficient air pressures are built up in bucket compartments to blow gas-laden air out between the compartment 35 covers and through the funnel holes into the spinning room, making working conditions very undesirable.

In the customary installations, the bucket is served from the top; that is to say, the machine attendant withdraws the wound cake from the top of the bucket. This requires the location of the bucket relatively high in the compartment so that the top end of the bucket clears the underside of the compartment cover by only a small 45 amount.

It is an object of this invention to provide improved ventilation of bucket compartments. Other objects of the invention will be in part apparent and in part set forth as the description 50 proceeds.

The object of this invention, generally speaking, is accomplished by making the outside of the bucket frustro-conical with the base of the cone at the bottom of the bucket, thereby causing 55 the air current to flow downward.

In the drawing, Figure 1 is a section through the center of a centrifugal bucket located in a bucket compartment; Figure 2 is a section through the center of a modified form of a bucket.

60 In Figure 1, 1 indicates a spinning bucket; 2 indicates a cover for the bucket; 30—31 indicate the interior of the bucket which is provided with a flare from bottom to top to permit withdrawal of the bucket cake; 40—41 indicate the 65 exterior of the bucket which is provided with a flare from top to bottom in order to direct the flow of air toward the ventilating duct at the bottom of the bucket; 61 are drainage channels in the walls of the bucket; 60 are holes through 70 the walls leading to the channels for draining the bucket interior; 80 indicates a bucket compartment; 83 indicates a cover for the bucket compartment; 84 indicates a hole in the bucket compartment cover through which a thread guide 75 may project into the interior of the bucket; 82 is an opening in the base of the compartment leading to a ventilating duct; 81 is the wall of the compartment above the duct.

75 The form of the invention just described functions as follows: As the thread is collected in the bucket, excess liquid from the thread is drained off through the holes in the bucket walls into the channels and is thrown toward the bottom of the bucket where it is drained off. The 80 ventilating duct in standard practice is exhausted by a fan and tends to withdraw the saturated air from the interior of the bucket compartment. The bucket is frustro-conical interiorly with a flare toward the top to allow the attendant to 85 remove the bucket cake and is frustro-conical exteriorly with the largest portion of the cone toward the bottom in order that the bucket may act as a blower and throw the saturated air in the compartment toward the ventilating duct.

90 In Figure 2 is shown a modified form of the invention wherein the bucket is provided with hollow walls to reduce its weight. In this figure, 95 50 are holes through the inner wall; 51 is a hollow space within the walls and 52 is a hole through the outer wall provided for the escape of fluid 100 into the bucket compartment.

An advantage is in improving the ventilation of a bucket compartment without the use of additional power either in the ventilating system 105 or in driving the buckets. Another advantage of the invention is a greatly improved ventilation of the spinning room and correspondingly improved working conditions. Another advantage of the invention is decreased crystallization in the 110

bucket compartment and decreased formation of salt crystals on the walls of the bucket with an accompanying decrease in consumption of power, particularly toward the end of the spinning cycle. Other advantages of the invention will be apparent.

As many apparently widely different embodiments of this invention may be made without departing from the spirit and scope thereof, it is to be understood that I do not limit myself to the specific embodiments thereof except as defined in the appended claims.

I claim:

1. In a spinning machine a bucket compartment ventilated toward the bottom and therein a centrifugal bucket having an interior flare from bottom to top and an exterior flare from top to bottom. 80
2. In a centrifugal bucket spinning machine a compartment, an opening therein to permit the expulsion of air therefrom, and means within the compartment to expel air therefrom comprising a centrifugal bucket having an exterior conically shaped, and having the base of a cone in close proximity to the said opening. 85
